UNITED STATES PATENT OFFICE

MILTON ALDEN, OF SPRINGFIELD, MASSACHUSETTS, ASSIGNOR, BY MESNE ASSIGNMENTS, TO RADIO INVENTIONS, INC., A CORPORATION OF NEW YORK

ACOUSTICAL INSTRUMENT

Application filed April 7, 1927. Serial No. 181,754.

The one object of my invention is to produce a radio broadcast receiver in combination with an electrical phonograph of high quality.

Another object is to produce a combination as described above from which the radio tuning elements and their associated component parts may be removed as a unit in order that the program to be received may be controlled from a distance.

Still another object is to produce an apparatus of the type described having extremely high tonal quality both in respect to the reproduction of mechanical records and the reproduction of radio broadcasts.

My invention consists chiefly of the combination of turntable electrically driven by the type of motor frequently employed in alternating current integrating watt-meters, a governor, and a stylus operated magnetic pick-up associated therewith, a high quality amplifier for use for the reproduction of both records and broadcasting, a high grade loud speaker which may be of the cone type, a removable container carrying the tuning elements and their associated apparatus, and suitable energizing sources for the radio apparatus all contained in one cabinet.

I thus produce a unit in which many of the component parts are used both for radio reproduction and for record reproduction thereby considerably lowering the manufacturing cost, and due to the removable feature of the tuning element, the operation of the device as a radio receiver may be controlled from a distance.

Referring to the drawings, Fig. 1 is a perspective view of one embodiment of my invention, showing the radio control box removed from the cabinet.

Fig. 2 is a detail of a part of the phonograph mechanism.

Fig. 2a is a perspective view of certain modified details.

Fig. 3 is an elevation of the motor and a part of the turntable.

Fig. 4 is a partially sectional front view with the cone of the speaker removed.

Fig. 5 is a partially sectional side view of the apparatus.

Fig. 6 is a schematic wiring diagram showing one of many possible arrangements of the transfer switch.

The cabinet 10 may be of any suitable design and provided with a number of chambers or compartments. One may preferably be furnished with a loud speaker having a grill or outlet 11 at one side. An upper chamber has a hinged cover 12. The cabinet may also be provided with an inner closure 13 having a recess or compartment 14 adapted to hold the tuning box 15 so that its panel 16 will be substantially flush with the closure 13. Upon a shelf 17 in a central compartment having a door 12' may be mounted an audio frequency amplifier 18 which may preferably be of the type disclosed in my Patent 1,678,717. A chamber may be provided in the bottom of the cabinet 10 for the power sources for the vacuum tubes used, here indicated as the cathode heating battery 19 and the anode supply batteries 20 and 21, but it should be understood that battery eliminators, motor generators, or other means of power supply may be employed.

The loud speaker movement 22 may be secured to the wall 23 of the recess or well 14 and its cone-like diaphragm 22' may be secured to or behind the outer edge of the grill 11.

The turntable 24, which is preferably constructed of aluminum, is mounted in the central compartment upon the horizontal shaft 25 and this shaft may be provided with spring members such as 26 and 27 for frictionally engaging the central aperture of the record 28 and holding it in place.

The disc 24 is somewhat larger than the largest record to be used and its free edge passes between the pole tips 29, 30, 31, 32 and 33 of the eddy current induction motor drive until 34 which may be suitably mounted within the cabinet as by the bracket 35. The disc 24 may be provided with a suitable governor such as the friction governor 36 which may be mounted as shown upon the under side of the closure 13.

Across the face of the disc 24 and record 28 extends the bar 37 which may be pivotally mounted as at 38 so that it may be swung

outward when it is desired to change records. The end of this bar when in playing position engages with the spring clips 39 and 40. This bar carries the carriage 41 which may be supported from the bar by grooved rollers 42 and 43 allowing it to move easily along the bar 37 and to swing about this bar. Depending from the carriage 41 is the stylus operated magnetic pick-up 44 which should be so balanced and mounted as to cause the stylus 45 to engage the grooves of the record 28 with proper pressure. This pick-up may be of any suitable type such as that disclosed in my Patent 1,756,966.

15 The tuning box 15 is attached to the cabinet 10 by a flexible cable 46 which contains all necessary leads such as antenna, ground, battery and detector out-put leads. Of course this cable may be wound on a suitable reel. 20 This tuning box may contain suitable radio frequency amplification and detection apparatus 51 and 52 respectively with their tuning and volume control devices which may be of any suitable type. I have shown a volume control at 47, a detector rheostat at 48 and as a tuning control, indicated at 49, I prefer to use the localized control disclosed in my co-pending applications #154,689, filed Dec. 14, 1926, or 163,196 filed Jan. 24, 1927.

25 30 A plate battery 53 is provided for the detector.

35 A switch 50 is provided having three positions. In the central position all current is turned off. In the phonograph operating position the tubes of the audio frequency amplifier are lighted and the alternating current house line 60 is connected suitably to the disc driving magnet 34. In the radio operating position all the tubes in the apparatus are lit and the driving magnets 34 are disconnected. This switch also effects the connection of the in-put of the audio frequency amplifier to either the detector out-put or the out-put of the magnetic pick-up 44 appropriately.

40 45 In operation as a phonograph, the bar 37 is disengaged from its clips 39 and 40, and is swung horizontally outward until a record such as 28 can be conveniently snapped on to the shaft 25 so as to be held against the turntable 24 by the springs as 26 and 27. The rod 37 is then swung back to engage the spring clips 39 and 40. The magnetic pick-up 44 is raised from the record 28 and moved along the bar 37 until the stylus 45 is opposite the outer grooves of the record. The switch 50 is then adjusted to the "phonograph" position thus connecting the input of the audio frequency amplifier 18 to the pick-up 44, connecting the motor 34 to the alternating current lines and lighting the filaments of the tubes of the amplifier 18.

50 55 60 When used as a radio receiver the switch 50 is placed in the "radio" position, thus disconnecting the motor 34, lighting the tubes of

both the amplifier 18 and the control unit 15 and transferring the input of the audio frequency amplifier 18 from the pick-up 44 to the detector out-put of the radio frequency tuning unit.

65 70 In Fig. 2a I have shown certain modifications of details which are of considerable value. In this case, I have shown the guide rod 37 mounted behind the turntable or record holder 24. The pick-up device 44 is supported by a sort of gooseneck carriage 41' which travels on this rod 37' so that the goose-neck extends around the edge of the record holder. Preferably, this guide rod 37' is inclined somewhat so that gravity may assist the movement of the pick-up in the grooves in the face of the record.

75 80 In some of the modern records the grooves are made extremely fine and consequently they are poorly adapted to the feed of the needle of the pickup. The inclination of the guide track serves to provide a continual tendency for the pick-up to move towards the center of the record, thus preventing the needle from jumping out of the groove. It has been found that records which cannot be played on the usual horizontal turntable on account of this tendency of the needle to jump from the groove, can be very well played on the vertical turntable of my invention.

85 90 95 In Fig. 2a, I have also shown the motor 34 and the governor 36' both mounted on a casting or frame 35' which serves to support the turntable shaft 25. This arrangement facilitates construction and installation of the parts.

100 105 The vertical record arrangement has an additional advantage in that it does not tend to collect dust and grit, which act as abrasives and tend to damage the records when they are used on horizontal plane machines.

110 115 This vertical arrangement of the record has a very substantial advantage in that it is possible to utilize a magnetic pick-up of a very substantial weight and efficiency and without damage to the records. The vertical arrangement makes it possible to balance the suspension so as to provide any desired pressure of the needle against the record.

120 125 A further advantage of the vertical record and straight guide rod is that the needle of the pick-up can be caused to remain tangentially to the groove of the record at all times, which is not possible with the usual type of swinging support.

130 135 The radio receiver with the portable control unit is claimed in my application Ser. No. 602,197 filed March 31st, 1932.

140 145 It should be understood that I do not wish to limit myself to the specific embodiments of my invention, as shown and described, except insofar as I do limit myself in the following claims.

I claim:

1. A combination radio broadcast receiver and phonograph comprising a motor driven phonograph record holder, an electro-magnetic pick-up coacting with a record on the holder, audio amplifying means connected to the pick-up, a loud speaker connected to the output of the audio amplifying means, power supply means for the amplifying means, a cabinet containing all of the foregoing elements in combination with a portable unit containing the following elements, namely, radio amplifying means, detecting means connected thereto, tuning means for the detecting circuit and volume control means, a cable connecting the parts in the portable unit and the parts located in said cabinet, and switching means for switching the loud speaker from the radio amplifying means to the phonograph pick-up.

2. An instrument of the character described, comprising a metallic turntable mounted on a horizontal axis, an induction motor stator having pole pieces coacting with both sides of one edge of the turntable for driving the same, a means for removably securing a sound record on said turntable, and a pick-up supported to move across the face of the record.

3. An instrument of the character described, comprising a turntable mounted on a horizontal axis, a guide rod mounted near said turntable, a carriage having a gooseneck extension projecting around the edge of the turntable, and an electric pickup supported by said gooseneck extension for coaction with the record on said turntable.

4. An instrument of the character described, comprising a turntable mounted on a horizontal axis, a guide rod mounted adjacent thereto, and inclined downwardly with relation thereto, a carriage mounted to travel on an incline on said guide rod, and a magnetic pick-up supported by said carriage and adapted to coact with the record on said turntable, whereby gravity assists in the movement of said pick-up across the face of the record.

5. An instrument of the character described, comprising a turntable mounted on a horizontal axis, an induction motor stator consisting of pole pieces and windings arranged on opposite sides of one edge of said turntable, a governor coacting with said turntable and a single mounting frame supporting said motor, said governor and said turntable.

6. A sound reproducing instrument comprising a substantially vertical turntable mounted on a substantially horizontal axis and provided with a metallic armature portion, an induction motor stator having pole pieces arranged on opposite sides of one edge of the metallic armature portion outside of the record holding portion of the turntable

and coacting with the armature portion of the turntable for rotating the same, means for supporting a sound record on said turntable, a pick-up device provided with a stylus for coaction with the sound record and means for guiding said pick-up device across the face of said record.

7. A reproducing device comprising a turntable whose plane of rotation is inclined more than 45° to the horizontal, means for rotating said turntable, a pick-up device having a stylus for coaction with a record supported on said turntable, a guide rod for said pick-up arranged in a plane substantially parallel to the plane of the turntable but inclined to the horizontal so that gravity aids the movement of the pick-up along said guide rod.

8. A combination radio broadcast receiver and phonograph including a motor driven phonograph record holder, an electric pick-up coacting therewith, a source of electric power, amplifying means and a loud speaker, a cabinet containing all of the foregoing elements, a portable control unit containing means for controlling the tuning of the receiver and volume control means and a cable connecting the portable unit and the cabinet and switching means for switching the loud speaker from the broadcast receiver to the phonograph.
